UNITED STATES PATENT OFFICE.

IVAR F. WARME AND ROBERT A. BLOOD, OF SYRACUSE, NEW YORK, ASSIGNEES TO
CONTINENTAL CAN COMPANY, INCORPORATED, OF SYRACUSE, NEW YORK, A
CORPORATION OF NEW YORK.

MARKING DEVICE FOR CAN-COVERS.

1,329,941.

Specification of Letters Patent.

Patented Feb. 3, 1920.

Application filed July 18, 1918. Serial No. 109,969.

To all whom it may concern:

Be it known that we, IVAR F. WARME and ROBERT A. BLOOD, citizens of the United States, residing, respectively, at Syracuse, 5 in the county of Onondaga, State of New York, have invented certain new and useful Improvements in Marking Devices for Can-Covers, of which the following is a description, reference being had to the accompanying 10 drawing and to the figures of reference marked thereon.

The invention relates to new and useful improvements in marking devices, and more particularly to a marking device which may 15 be used for placing an identifying mark on a metal can cover or the like.

An object of the invention is to provide a marking device wherein the implements for impressing the identifying mark in the cover 20 are movable with the cover at the time when the identifying mark is impressed into the cover.

A further object of the invention is to provide a marking device of the above character with means for feeding the covers one 25 at a time thereto and with means for sustaining the covers until they are gripped by the implements which impress the identifying mark in the cover, said sustaining 30 means being withdrawn to permit a movement of the cover with the marking implements at the time when the impression is made in the cover.

A still further object of the invention is 35 to provide a marking device of the above character with means for restacking the covers after they are marked.

These and other objects will in part be obvious and will in part be hereinafter more 40 fully disclosed.

In the drawings, which show by way of illustration one embodiment of the invention:

Figure 1 is a side view of the machine 45 having the improvements applied thereto;

Fig. 2 is an enlarged view, partly in vertical section, showing the marking implements and the sustaining finger for holding the covers until gripped by said implements;

50 Fig. 3 is a detail showing the gripping implements as engaging the cover and the sustaining finger for the cover just being withdrawn to release the cover;

Fig. 4 is a plan view of the upper portion of the machine;

55

Fig. 5 is a perspective view of the sustaining finger for the covers;

Fig. 6 is a perspective view of the operating cam for the sustaining finger;

Fig. 7 is a detail showing the marking 60 implements at the point when the identifying mark is completed; and

Fig. 8 is a plan view of the cover having an identifying mark compressed therein.

In carrying out the invention, the covers 65 are placed in a stack in a cover holder and are fed from this cover holder one at a time to the marking implements. The covers are fed by gravity, after being released by the marking implements and are sustained momentarily in position between the marking implements until said marking implements have moved to a point where the cover is gripped between the marking implements and then the sustaining finger is completely 75 withdrawn so that the cover may move on with the movement of the marking implements until maximum pressure is put to bear on the cover, the identifying mark fully impressed therein, and then the implements 80 continue their movements, the cover traveling therewith to a point where the covers are released. After the covers are released they are brought by gravity into a chute so constructed and arranged as to re-stack 85 the covers, and they may be taken from there for use in connection with closing machines or the like.

While the marking device has been referred to as being used for marking covers, 90 it is understood that this term is used purely for descriptive purposes, and that it is intended to include can ends, can caps, as well as can covers. As a matter of fact, the improved marking device may also be used 95 for marking metal articles of any character where it is desired to stamp or impress in the metal an identifying character.

Referring more in detail to the drawings:

100 The improved marking device consists of a main frame 1 which may be of any desired construction, and mounted on this main frame are suitable brackets 2 which carry a stack holder 3, and this stack holder, 105 as shown in the drawings, is inclined to the

horizontal so that the covers stacked therein will slide down the cover stack and rest against the retaining finger 4. The lower end of the stack rests against a releasing and separating disk 5. This releasing disk is mounted to rotate. Attached to the rotating disk is a rod wound so as to form a helix, which is indicated at 6 in the drawings. Coöperating with this helix are suitable supporting guides for the covers, and the covers are dropped one at a time into this helix, and as it rotates it feeds and spaces the covers and releases the same one after the other at equal intervals of time. As shown in Fig. 2 of the drawings, the covers while they are being fed along by the helix are supported by the guides 7. When the covers are released from these guides 7—7 and from the rotating helix, they drop into a guideway 8 which carries the covers by gravity between two marking implements 9 and 10. These marking implements 9 and 10 are mounted to rotate. The cover dropping by gravity into the guideway 8 strikes against the sustaining finger 11 and will be held by this sustaining finger until the marking implements have returned to the position shown in Fig. 7 where they grip the cover and then the sustaining finger releases the same.

30 The marking implement 10 consists of a supporting head in which one member of a die 12 is mounted, said die being held therein by a suitable means. This may be the male member of the die. The marking implement 10 is provided with a shank 14 which extends into a suitable socket formed in a shaft 15, and said stem is held in the shaft by a screw 16. The shaft 15 is mounted in suitable bearings in the frame and is 40 rotated either by hand or by power, as desired.

45 The marking implement 9 is of a similar construction and includes a female die 17 which is held in its socket by a suitable pin 18. The marking implement 9 is also provided with a stem 14, and this stem is held in a socket in the shaft 19 by a screw 16. The shaft 19 is also mounted in suitable bearings in the main frame, and this shaft 50 carries a gear wheel, indicated at 19^a in the drawings, which meshes with the gear wheel 19^b carried by the shaft 15 so that the two shafts rotate in exactly the same timing but in opposite directions. The shaft 19 rotates in a clockwise direction, while the shaft 15 rotates in a counterclockwise direction.

60 The can end or cover resting on the sustaining finger 11 is positioned so that the dies 12 and 17 as they come into intermeshing relation with each other will grip the middle of the can cover, and when these dies reach the position shown in Fig. 7 the metal of the cover will be indented so as to firmly fix in the cover an identifying mark. In 65 Fig. 8 of the drawings, the cover is shown at

C, and in this cover the identifying mark "C. C. C." has been impressed.

The sustaining finger 11 is adjustably secured to a suspended lever 20 by means of a clamping bolt 21 which passes through the slot 22 in the lever. A spring 23 presses against this lever and against an adjusting bolt 24 as an abutment. By turning the bolt 24, the tension of this spring may be increased or decreased, as desired. Mounted 75 on the lever 20 is a roller 25 which bears against the cam face 26 formed in the shaft 19. This cam face is shown in full lines in Fig. 6 of the drawings, and also in dotted lines in Fig. 2 of the drawings. The cam is 80 so positioned that as the shaft 19 turns, just as soon as the cover is gripped by the marking implements, the lever 20 will be swung outward at its lower end so as to release the cover, and this permits the cover to be moved 85 forward with the implements at the time the identifying mark is impressed in the cover. As soon as the cover passes the sustaining finger 11, the cam face 26 releases the roller 25 and permits the sustaining finger to swing 90 back in position to catch the next cover released by the helix.

The gear wheel 19^b meshes with a gear wheel 27 carried by a short shaft 28 mounted in suitable bearings formed in the bracket 95 2. This short shaft carries a beveled gear 29 which meshes with a beveled gear 30 on a shaft 31. The shaft 31 carries a gear 32 which meshes with a gear 33, and this gear 33 is mounted on a shaft 34 which carries the releasing disk and the helix. The releasing disk and the helix will, therefore, be operated in proper timing with the marking implements. After the covers are released from the marking implements, they 105 pass down into a receiving chute.

This receiving chute consists of side members 35 and a front plate 36. The rear wall of this chute is inclined slightly, as at 37, and to a greater extent, as at 38. The covers dropping by gravity slide along this 110 wall and owing to the inclination thereof these covers when they reach the rear end of the chute will slide one upon the top of the other in horizontal arrangement which 115 restacks the covers. The restacked covers rest on the slide 40 which may be withdrawn at will and the stack removed from the guides.

The cover feed shown and described in 120 detail above consisting of the releasing disk and the helix forms no part of the present invention *per se*, and it will be understood that other cover feeding devices may be used, the essential feature thereof consisting in feeding the covers one after the other in spaced timed relation to each other so that these covers may be operated upon by the marking implements and then restacked. While, also, the marking devices are shown 130

as operating upon a cover dropped by gravity between the marking devices, it will be understood that these marking implements may be otherwise arranged, the essential 5 feature here consisting in the opposed dies which travel with the cover at the time that the identifying mark is impressed therein.

Having thus described the invention, what is claimed as new is:—

10 1. A marking device for can covers including in combination, coöperating rotating dies for impressing an identifying mark in the metal of the can end, feeding means for presenting can ends continuously and in 15 succession one after the other to said marking dies, and means for engaging the forward edge of the can ends and timing said can ends relative to the dies.

2. A marking device for can covers including in combination, coöperating rotating dies for impressing an identifying mark in the metal of the can end, feeding means for presenting can ends continuously and in 25 succession one after the other to said marking dies, said dies being constructed and timed so as to serve as the sole feeding means for the can end during the operation of the dies thereon.

3. A can marking device including in 30 combination, oppositely rotating shafts, marking implements including coöperating dies carried by said shafts and timed so that said dies grip the cover and impress an identifying mark therein as the cover passes 35 between the shafts, means for sustaining the cover until gripped by the dies, and means for withdrawing said sustaining means so as to permit the cover to move with the dies at the time the identifying 40 mark is impressed therein.

4. A can marking device including in combination, oppositely rotating shafts, marking implements including coöperating dies carried by said shafts and timed so 45 that said dies grip the cover and impress

an identifying mark therein as the cover passes between the shafts, means for sustaining the cover until gripped by the dies, means for withdrawing said sustaining means so as to permit the cover to move 50 with the dies at the time the identifying mark is impressed therein, and means for feeding the covers at proper spaced time intervals to the sustaining means.

5. A can marking device including in 55 combination, oppositely rotating shafts, marking implements including coöperating dies carried by said shafts and timed so that said dies grip the cover and impress an identifying mark therein as the cover 60 passes between the shafts, means for sustaining the cover until gripped by the dies, means for withdrawing said sustaining means so as to permit the cover to move with the dies at the time the identifying 65 mark is impressed therein, means for feeding the covers at proper spaced time intervals to the sustaining means, and means for receiving the covers and restacking the same 70 after they have been marked.

6. A can marking device including in combination, oppositely rotating shafts, marking implements including coöperating dies carried by said shafts and timed so that said dies grip the cover and impress an 75 identifying mark therein as the cover passes between the shafts, means for sustaining the cover until gripped by the dies, means for withdrawing said sustaining means so as to permit the cover to move with the dies 80 at the time the identifying mark is impressed therein, means for feeding the covers at proper spaced timed intervals to the sustaining means, and means for receiving the covers after released by the dies for 85 restacking the same.

In testimony whereof we affix our signatures.

IVAR F. WARME.
ROBERT A. BLOOD.
